PIPE HOLDER

William A. Sigrist, Madison, Wis.

Application March 3, 1950, Serial No. 147,459

1 Claim. (Cl. 211—114)

1
This invention relates to a device for removably retaining smoking pipes and tobacco especially designed for use in moving vehicles such as automotive vehicles, boats, and the like.

The primary object of the invention is to provide a holder which is attractive in appearance, simple in design and construction, inexpensive to manufacture and very efficient in removably retaining smoking pipes which will minimize rattling of the pipes in the holder without damage or injury to the pipes.

Another object of the invention is to provide a pipe holder comprising a housing having a top, bottom and side walls, a horizontal partition between the top and bottom walls forming a tobacco pouch-receiving chamber at the bottom of said housing, a plurality of spaced vertical spacer plates between the top wall and the partition forming compartments, and resilient means in each of said compartments for removably retaining the stems of pipes therein.

These together with various ancillary objects and features of the invention which will later become apparent as the following description proceeds, are attained by the device, a preferred embodiment of which has been illustrated by way of example only in the accompanying drawings, wherein:

Figure 1 is a perspective view of the holder;

Figure 2 is a sectional view taken on the line 2—2 of Figure 3; and

Figure 3 is a sectional view taken on the line 3—3 of Figure 2.

Specific reference is now made to the drawings. In the several views in the accompanying drawings and in the following specification similar reference characters indicate corresponding elements throughout.

The holder of the present invention is indicated generally at 10 and is a housing which may be fabricated of lightweight metals, plastics, or wood. The housing comprises side walls 12 and 14, an inclined lower shelf 16 which is preferably upwardly and forwardly inclined for proper positioning on the dash of an automotive vehicle, and a top wall 18. Between the top and bottom walls and parallel to the former is a horizontal bottom wall 20 which is longer than the top for a reason soon to appear. To the rear edges of the side walls 12 and 14, the inclined shelf 16 and the bottom wall 20 is secured a back wall 22 forming therewith a tobacco pouch-receiving compartment 24 open at its forward end. Appropriate brackets 26 may be attached to the side walls to secure the holder to the dash of the vehicle.

2
The forward edge of the top wall is arcuated, as shown clearly in Figure 2, so that it is longer at the center and becomes progressively shorter at the edges adjacent the side walls 12 and 14 to accommodate pipes having varying stem lengths. This forward edge is also provided with arcuate recesses 28 adapted to engage the bowls 30 of smoking pipes 32. At the forward edge of the top wall between the recesses, a plurality of vertically extending, spaced parallel plates 34 are secured between the bottom wall 20 and top wall 18 to provide separate pipe-stem receiving compartments 36.

In each compartment 36 is provided an arcuate leaf spring 38 which is secured only at one end 40 adjacent the forward edge of the top wall 18, the other end being upturned as at 42 to provide a bowed portion 44 adapted to press against and resiliently retain the stem 46 of the pipe as shown clearly in Figure 3.

In use, the holder is positioned on and secured to the dash of an automatic vehicle in a manner readily understood. The pipe stems 46 are pushed into the compartments 36 to grippingly and releasably engage the bowed portions 44 of the leaf springs 38. The bowls 30 rest on the bottom wall 20 and also engage the recesses 28 of the top wall 18 to prevent rattling of the pipes in the holder as the vehicle moves. It is also evident that the holder can retain a number of pipes of different length.

It will be understood that the spaced parallel plates may be dispensed with and the holder reduced in dimensions to support only one pipe, it being further understood that the forward edge of the reduced top wall will be curved inwardly from the side walls 12 and 14 to engage the bowl of the pipe just as the recesses 28 engage the plurality of pipe bowls.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A pipe holder comprising a housing including a top, bottom and side walls and having an open back, said bottom wall being longer than said

top wall to provide a bowl supporting ledge, vertical spaced plates connecting said bottom and top walls and dividing the housing into a plurality of compartments, and an arcuate leaf spring in each compartment secured at one of its ends to the inner surface of said top wall adjacent its forward edge and adapted to yieldingly retain a pipe stem in each compartment, the forward edge of said top wall between said plates including arcuate recesses for engaging pipe bowls 10 to limit the lateral and inward movement of the pipes.

WILLIAM A. SIGRIST.
